Primary Examiner — Holly E Thurman*Assistant Examiner* — Kristopher Michael Blechschmidt(74) *Attorney, Agent, or Firm* — Hawaii Patent Services; Nathaniel K. Fedde; Kenton N. Fedde(57) **CLAIM**

The ornamental design for an animal repellent device, as shown and described.

DESCRIPTION

FIG. 1 is a front, right, top perspective view of an animal repellent device, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The dashed broken lines in the figures are for the purposes of illustrating portions of the animal repellent device that form no part of the claimed design.

1 Claim, 8 Drawing Sheets(56)
